ATTORNEY

UNITED STATES PATENT OFFICE.

WILLIAM WESTENFIELD, OF CORONA, SOUTH DAKOTA.

DESIGN FOR AN INDICATOR FOR AUTOMOBILES.

51,360.

Specification for Design.

Patented Oct. 9, 1917.

Application filed June 8, 1917. Serial No. 173,245. Term of patent 14 years.

To all whom it may concern:

Be it known that I, WILLIAM WESTENFIELD, a citizen of the United States, residing at Corona, in the county of Roberts and State of South Dakota, have invented a new, original, and ornamental Design for Indicators for Automobiles, of which the following is a specification, reference being had to the accompanying drawing, forming a part thereof.

The figure is a perspective view of an indicator for automobiles, showing my new design.

I claim:

The ornamental design for an indicator for automobiles, as shown.

WILLIAM WESTENFIELD.
